PARENTERAL SOLUTION BAG OR SIMILAR DEVICE

David Bellamy, Jr., Glenview, Ill., assignor to Baxter Laboratories, Inc., Morton Grove, Ill., a corporation of Delaware

Filed Dec. 28, 1964, Ser. No. 83,168

Term of patent 14 years

(Cl. D83—1)

The side not shown is substantially the same in appearance as the side shown.

I claim:

The ornamental design for a parenteral solution bag or similar device, substantially as shown and described.
